UNITED STATES PATENT OFFICE.

EPHRAIM H. RODEN, OF CHICAGO, ILLINOIS.

MAILING DEVICE.

1,148,927.

Specification of Letters Patent.

Patented Aug. 3, 1915.

Application filed March 4, 1912. Serial No. 681,663.

To all whom it may concern:

Be it known that I, EPHRAIM H. RODEN, a citizen of the United States, residing at Chicago, county of Cook, and State of Illinois, have invented certain new and useful Improvements in Mailing Devices, of which the following is a specification.

The invention relates to mailing devices, and has for its object to provide improved, simple, efficient and economical means for inclosing mail matter of various descriptions, which said mail matter will be capable of being sealed for secret transportation or handling, and will readily show any improper attempt at opening by unauthorized persons, and being at the same time provided with improved means for enabling the sealing means to be broken and the contents removed without the employment of any instrumentalities exterior to the mailing devices except the hand of the operator.

A further object of the invention is to provide an improved insert adapted to be used in connection with mailing envelopes of the usual or any desired form and construction which when forcibly removed from the envelop will break the seal of same to render the contents thereof easily removable.

Other objects will appear from the description contained in the following specification, which includes the drawings, showing the preferred form of the invention, and the appended claims.

In the said drawings Figures 1 and 2 are views showing an opening insert and envelop, the envelop being provided with a transparent portion to disclose the address on the inclosure and an opening in the insert adapted to register with the transparency in the envelop. Fig. 3 is a sectional view through Fig. 2 on line 3—3. Figs. 4 to 7 are similar views of an opening insert and envelop therefor with the transparency pasted on the insert over the opening therein, while the address opening in the envelop is not covered. Figs. 8 to 10 inclusive are views showing the insert modified to correspond to the form shown in Fig. 1, but with a return reply card detachably secured thereto. Figs. 11 and 12 illustrate a modi-

fied form of insert folded or of two thicknesses, and Fig. 13 is an assembled view showing the manner in which the insert of Figs. 11 and 12 is applied to the envelop.

In Fig. 2 the mailing device is shown in 55 the preferred form complete with the insert, the detail of which is illustrated in Fig. 1.

The envelop is of the usual or any desired form, and is designated generally by reference character A, in Fig. 1 being rectangular in form and having a portion of the material adjacent the edge along which the envelop is to be opened cut away as indicated at 10, in order to expose a portion of the insert 11 as indicated at 11^a, which exposed portion may be grasped by the operator in pulling the insert from the envelop for the purpose of opening it.

The insert 11 may be made of any material suitable for inserting within the envelop which shall be light and at the same time have sufficient strength and rigidity to cause it to open or cut one end of the sealed envelop when it is withdrawn therefrom. The form of the envelop shown in Fig. 2 70 being the regular commercial envelop, and of somewhat greater length than width, will require an insert of corresponding form in general outline, although somewhat smaller, as illustrated in Fig. 1; when the general 75 form of the insert is rectangular, as illustrated in Fig. 1, the edge of the envelop at one end thereof will be cut away as indicated at 10, in order to expose the insert as indicated at 11^a in Fig. 2.

The cut away portion 10 of the envelop may be of any desired width as is usually sufficient to enable the operator to grasp an exposed portion of the insert. It is preferred that the co-operating edge 11^a of the 90 insert shall be cut on a right line as illustrated in Figs. 1 and 2, so that when inserted within the envelop adjacent the opening 10 it shall be a trifle longer than the clearance of the opening, this being shown 95 more clearly in the assembled view in Fig. 2. Such a construction makes it necessary for the operator on first pulling the insert from the envelop to pull upon the insert with sufficient force to cause it to rupture or cut 100

the material in the fold at the end of the envelop adjacent the opening 10. This serves to render the envelop somewhat safe against accidental opening. Beyond the rectangular portions 11^a at the end of the insert the material of the insert is cut along angular lines, and preferably broken lines, as indicated at 11^b, 11^c and 11^d, extending outwardly from the rectangular portion 11^a. The angular portion or peak at the junction of the lines 11^c and 11^d, when the insert 11 is of suitable material, as Bristol board, furnishes a pointed opening means which will pierce through the paper at the end of the envelop and the angular converging edges 11^c 11^d and the angular edge 11^b will then cut out the end of the envelop as the insert is pulled outwardly, as illustrated in dotted lines in Fig. 2.

In order to make it possible for the operator to hold the envelop conveniently while the insert is being pulled therefrom, the opposite end of the insert 11 is preferably cut away, usually about the middle thereof, as indicated at 11^e. In the envelop illustrated in Fig. 2, to which the insert 11 is shown applied, the last sealing flap which is usually sealed after the various inserts are placed in the envelops, is indicated by the reference character 12, while the end flaps 13—14 and the first side flap 15 are usually folded and sealed before the insert is placed in the envelop.

In the use of this improved mailing device the insert 11 may be placed in the envelops at the time they are made up, or they may be placed in the envelop at the time the letters or other matter desired to be mailed are inserted in the envelop.

The invention may readily be adapted for use in connection with envelops provided with elongated openings for disclosing an address on an inclosure, or an envelop provided with a transparency through which the address of the inclosure may be readable from the outside of the envelop. In Fig. 1 an insert is provided with an elongated portion of the insert cut away, as indicated at 40. This form of insert is adapted to be used in connection with an envelop as indicated by the reference character 41 in Fig. 2, the same being provided with a transparent portion registering with the elongated opening 40 in the insert, such transparent portion being indicated at 42, and in the views of Figs. 2 and 3, the transparency 42 is shown attached to an opening in the envelop although an envelop provided with a transparency of any desired construction may be employed.

In Figs. 4 to 7 inclusive an envelop and insert of the general form illustrated in Figs. 1 and 2 is shown, in which the envelop is provided with an elongated opening as indicated at 43. The insert shown in Fig.

4 is likewise provided with an elongated opening registering with the opening 43 in the envelop, when the insert is within the envelop. This opening is indicated by the reference character 44 in Fig. 4 and is in this modification of the invention covered by a transparent film of paper or other suitable material, as indicated at 45.

In making inserts of the form shown in Fig. 4 it is preferred that the transparent material shall be applied to the strip of paper from which the inserts are cut in a continuous strip after which the inserts are cut from the strip. In Fig. 4 the film 45 is shown as covering approximately the lower half of the reverse side of the insert, the top side of the film being indicated by the dotted horizontal line and the film extending from this line to the bottom of the insert and hence covering the opening 44 in the insert. When an insert of the form shown in Fig. 4 is used in connection with an envelop as shown in Fig. 6, the inclosure will be placed beneath the insert, and in this manner the address of the inclosure will be readable through first the opening 43 in the envelop, and second the transparent covered opening 44 in the insert which will protect the inclosure.

In Figs. 8 to 10 inclusive is shown a slight modification of the forms of the invention shown in the Figs. 1 to 7, the insert being provided with holding means as the tongues or ears 35, 36, 37. In this form of insert there is also a cut away portion as indicated at 40, similar to the cut away portion in Fig. 1, the same being adapted to register with the transparency in the envelop, as illustrated in Fig. 10, through all of which the address of the inclosure may be readable from the outside of the envelop. In Fig. 9 an inclosure 38 is shown secured to the insert by ears 35 to 37 inclusive. In this form of double insert approximately one-half of the body portion of the insert may be utilized for a return postal card, the same being indicated by the reference character D, and adapted to be torn from the body of the insert along the perforated line indicated by the reference character 55 in Figs. 8 and 9.

In Figs. 11 to 13 inclusive, I illustrate the manner of cutting another modified form of the insert from a continuous strip of paper, the insert in this form being adapted to be folded upon itself to produce a double thickness, which makes it possible to use a much thinner and cheaper stock of paper than where it is necessary to depend upon a single thickness of paper for opening the insert.

In Fig. 12 the general form of cutting the blanks from a continuous strip of paper is illustrated in order to produce the insert shown in Fig. 11. In cutting these inserts the strip is twice the width of the insert de-

sired, and the cutting is preferably along broken lines corresponding to the outline of the cutting edge of the insert of Fig. 1. The continuous strip of material is preferably 5 scored along the line indicated by the reference character 70, so that the completely severed insert may be folded in the manner illustrated in Fig. 11. From the cutting edge of each of the inserts and extending 10 inwardly for a short distance along the scored line 70, the inserts are preferably cut as indicated at 71 and then scored from the inner end of the cut 71, as indicated by the dotted line 72, to the outside edge of the 15 insert. And the scored portion of this half of the insert, indicated by the reference character 73, may then be folded in the manner illustrated in Fig. 11, in order that an inclosure or letter may be placed beneath the 20 folded portion 73, so that when an operator grasps the exposed rectangular forward end of the insert and pulls the insert from the envelop, breaking the end thereof, the inclosure will be removed from the envelop 25 with the insert. The double form of insert shown in Figs. 11 and 12 may be provided with the elongated opening of the insert shown in Fig. 4 and covered with transparent material by applying a continuous 30 strip of transparent material to the strip from which the inserts are cut before the inserts are severed from the strip following the method of manufacture heretofore described in connection with Figs. 4 to 7 inclusive. 35

Fig. 13 is an assembled view of a mailing device in which the envelop is of the form of the envelop shown in Fig. 6, and containing the insert of Fig. 11 therein.

40 In all of the forms of the insert illustrated I have shown a rectangular portion on the insert adapted to be accessible through a cut-away portion in one end of the envelop. In order that persons not entirely familiar with 45 the use of the device may understand its operation I prefer to designate the accessible portion of the insert which is to be grasped by the operator in opening the envelop by printing on the accessible portion the word 50 "Pull" or other suitable designation, as illustrated in the drawings. It will also be noted that in the various forms of the insert I have shown embodying the invention the opposite end of the insert to the rectangular 55 portion accessible to the operator is cut away to enable the operator to grasp the envelop and firmly hold it without at the same time binding the insert between his fingers. In all of the forms of the invention 60 I have shown this cutaway portion of the insert as at the middle of one end and I prefer to mark the envelop on the outside with some suitable designation, preferably the word "Pull", and by these marks or 65 designations the person desiring to open the

envelop will know the portions of the insert and envelop to be grasped in opening the envelop.

In order that the invention may be understood, the details of preferred embodiment 70 thereof have been specifically described. It will be apparent that other modifications may be employed without departing from the purpose and scope of the invention. 75

What I claim is:—

1. A mailing device comprising an envelop having an elongated opening in one side through which an address on an article in the envelop is readable, an insert in said envelop and adapted to facilitate opening 80 the envelop, there being an opening in said insert registering with the opening in the envelop, and a transparent sheet over the opening in the insert and secured to the edges of the latter. 85

2. A mailing device comprising an envelop having an elongated address exposing opening in one of its sides, an insert in said envelop having a portion thereof accessible from the outside of the envelop and one of 90 its edges adapted to sever the envelop upon removal from the latter, there being an opening through said insert registering with the opening in said envelop, and a transparent sheet over one of said openings preventing removal of articles from the envelop through said openings. 95

3. A mailing device comprising an envelop having a portion of the material adjacent one edge thereof cut away, there being an elongated opening in the face of the envelop through which the address on an inclosure is readable, an insert adapted to be placed within the envelop and having a portion thereof accessible through the cut 100 away portion in the edge of the envelop, the said insert being of relatively firm material and having the edges thereof beyond the cut away portion in the envelop angularly disposed to form cutting edges for rupturing 105 and cutting the side edge of the envelop on the edge adjacent the cut away portion, there being an elongated opening in the body of the insert adapted to register with the said elongated opening in the face of 110 the envelop, and a transparent member supported by the insert over the said elongated opening therein. 115

4. The combination of an envelop having an opening in one edge thereof; and an insert in the envelop having a cutting edge partially exposed through said opening and disposed substantially parallel with the edge of the envelop containing said opening, said 120 partially exposed edge being slightly longer than the opening and having its ends hidden by and engaging portions of the envelop adjacent said opening, there being a cutting edge on the insert at each end of said partially exposed cutting edge disposed 125 130

angularly to the latter, the hidden ends of said first mentioned cutting edge being adapted to provide shoulders for preventing the second mentioned cutting edges from accidentally cutting the envelop.

In testimony whereof I have signed my name to this specification, in the presence of

two subscribing witnesses, on this 28th day of February A. D. 1912.

EPHRAIM H. RODEN.
